DISPENSER

Clarence S. Grant, Belfast, Maine

Application November 13, 1936, Serial No. 110,753

4 Claims. (Cl. 221—23)

This invention appertains to new and useful improvements in means for conveniently dispensing oil which is ordinarily available in quarts or other size cans at gasoline stations.

5 The principal object of the present invention is to provide a combined oil dispenser and can opener wherein a can of oil such as is now sold at gasoline stations can be placed and conveniently opened therein and dispensed therefrom without causing inconvenience or soiling the attendant.

These and various other important objects and advantages of the invention will become apparent to the reader of the following specification.

15 In the drawings:—

Figure 1 represents a front elevational view of the dispenser with a can therein.

Figure 2 represents a vertical sectional view through the dispenser and showing a can therein.

20 Figure 3 is a horizontal sectional view on the line 3—3 of Figure 2.

Figure 4 is a horizontal sectional view on the line 4—4 of Figure 2.

Figure 5 is a perspective view of the platform.

25 Figure 6 is a perspective view of the retaining tongue.

Referring to the drawings wherein like numerals designate like parts, it can be seen that numeral 5 represents a cylindrical shell having the bottom wall 6 raised from the lower end of the shell 5. An elbow 7 extends from the bottom 6 and has its lower end opening through the lower portion of the shell 5 and from this extends the flexible conduit 8 terminating in the discharge nozzle 9 which can be held in the retracted position shown in Figure 2 by the hook member 10 projecting from the can retaining tongue 11. This tongue 11 has a broad lower portion A which is attached by rivets 12 to the upper portion of the shell 5. The upper portion of this tongue is reduced as at b and the upper extremity is bent to form an inwardly disposed hook 13 for engaging over the upper edge portion of a can 14.

45 The can as shown in Figure 2 is to sit upon the circular platform 15, which platform is provided with a plurality of depending pin members 16 slidably disposed through L-shaped brackets 17 on the inside of the shell 5. Coiled compressible springs 18 are provided on the pins 16 and interposed between the lower side of the platform 15 and the bracket members 17.

Upstanding lugs 19 are provided on the peripheral portion of the platform 15 so as to hold the can 14 in position. Obviously the springs 18

serve to urge the platform 15 upwardly so that the upper end of the can will be engaged tensionally with the hook 13.

The outside of the shell 5 is provided with a conventional handle 20. As is clearly shown in Figure 5 and also in Figure 2 the platform 15 is provided with an elongated opening 21 through which the arcuate-shaped cutter 22 is slidably in its movement to reach and pierce the bottom of the can 14. As is clearly shown in Figures 2 and 4, this arcuate-shaped cutter 22 is provided with depending leg members 23 connected or bridged at their lower ends as at 24. A neck member 25 on the bridge member 24 carries the valve member 26, so that when the cutter is in lowered 15 position, the closure 26 is over the upper end of the elbow 7 preventing any discharge of oil from the shell 5. One leg of the cutter 22 has the rack 27 secured thereto and with this meshes the pinion 28 on the shaft 29, which shaft is 20 journaled through arms 30 projecting laterally from the supporting brackets 31 which carry rollers 32 against which the rack can rise. The shaft 29 at one end extends through the side of the shell 5 and is equipped with the hand 23 crank 33.

It can now be seen, that when a can 14 has been properly placed on the platform 15 and engaged with the hook 13, rotation of the shaft 29 by the crank 33 will result in the elevation 30 of the cutter 22 and the consequent piercing of the bottom of the can with the result that the can will empty into the shell 5 without any chance of splashing or inconvenience to the attendant. The oil can then be conveniently dispensed from the shell 5 through the conduit 8.

To prevent any leakage from the shell 5 around the shaft 29, a packing block 29a is provided on the shaft and is caused to bear snugly against the shell 5 through the action of spring 29b which is 35 situated on the shaft.

While the foregoing specification sets forth the invention in specific terms, it is to be understood that numerous changes in the shape, size and 45 materials may be resorted to without departing from the spirit and scope of the invention as claimed hereinafter.

What is claimed is:—

1. A dispenser of the character described comprising a shell having a handle, a bottom for the shell, a discharge conduit extending from the bottom, a vertically movable cutter in the shell, means on the outside of the shell for operating the cutter, a can supporting platform in the shell 55

having an opening therein through which the cutter can move.

2. A dispenser of the character described comprising a shell having a handle, a bottom for the shell, a discharge conduit extending from the bottom, a vertically movable cutter in the shell, means on the outside of the shell for operating the cutter, a can supporting platform in the shell having an opening therein through which the cutter can move, and a resilient support for the platform.

3. A dispenser of the character described comprising a shell having a handle, a bottom for the shell, a discharge conduit extending from the bottom, a vertically movable cutter in the shell, means on the outside of the shell for operating the cutter, a can supporting platform in the shell having an opening therein through which the

cutter can move, said cutter being provided with a rack, a gear meshing with the rack, said means further including a shaft on which the gear is secured and a hand crank at the outer end thereof.

4. A dispenser of the character described comprising a shell having a handle, a bottom for the shell, a discharge conduit extending from the bottom, a vertically movable cutter in the shell, means on the outside of the shell for operating the cutter, a can supporting platform in the shell having an opening therein through which the cutter can move, an upstanding hook member on the upper portion of the shell for engaging the upper portion of a can supported on the platform, and a spring support for the platform.

CLARENCE S. GRANT.
